PROCESS FOR THE MANUFACTURE OF CARBURETED WATER GAS USING HEAVY OIL

Edwin L. Hall, Philadelphia, Pa., assignor to The United Gas Improvement Company, Philadelphia, Pa., a corporation of Pennsylvania

Application February 9, 1931, Serial No. 514,463

5 Claims. (Cl. 48—208)

The present invention relates to the manufacture of carbureted water gas.

The principal object of the invention is the provision of an improved method of and apparatus for the manufacture of carbureted water gas which is especially adapted to the employment of heavy oils and residuums as carbureting material.

By heavy oils and residuums, I mean to include those oils which when vaporized in the ordinary checker filled carburetor produce excessive carbon deposition on the checkerbrick and lead to the collection, on the checkerbrick, of excessive quantities of ash and fuel from the generator due to deposited pitch from the oil. These heavy oils vary greatly in composition, but the term will be understood by those skilled in the art. As an example may be mentioned the so-called bunker oils. These may consist of topped crude oils and may or may not contain varying quantities of cracker tar. On vaporization and cracking to produce gas they yield comparatively large quantities of coke as compared with gas oil.

Due to the undue deposition of material in the checkerbrick with consequent stoppage of the gas passage, the vaporization of these heavy oils in the ordinary checker-filled carburetor is not the best practice. Better methods have been developed. For instance, vaporizing the oil on the top of the generator fuel bed after the top of the fuel bed has been especially heated by secondary combustion of the producer gas generated by the primary air blast during the blow—or vaporizing the oils by spraying them through a nebulizing spray into an empty carburetor or the employment of both of these methods.

Whichever method is employed it is a characteristic of these oils that although their rapid vaporization requires a high temperature the resultant oil vapors, for proper fixing, should not be exposed to as high a temperature as the vapors of ordinary gas oil.

In the use of ordinary gas oil the oil is vaporized during the run (often only during the up-run) in the higher temperature heat storage in the top of the carburetor, and with the water gas the resultant oil vapors traverse the path of the blast gases through the carburetor and superheater without overcracking. The temperature conditions set up in the carburetor and superheater by the blasting operation are not excessive for the proper fixing of the gas oil vapors.

The usual cycles of operation comprise an air blasting of the fuel bed, combustion of the resultant producer gas and the storing of its heat in the carburetor and superheater, an uprun with

steam supplied to the base of the generator, the carbureting of the resultant water gas in the carburetor and the superheater, with oil sprayed into the carburetor, and a down or back run. In the case of the down run, steam is supplied to the top of the fuel bed, and the resultant water gas either led through the carburetor and superheater and carbureted with oil sprayed into the carburetor, or led directly from the base of the generator to the washbox. In the case of the back run, the steam is supplied to the superheater top and superheated in passage through the superheater and carburetor, the resultant water gas passing from the base of the generator to the washbox.

In the use of heavy oil however, the customary methods of gas and vapor flow, lead to overcracking of the oil vapors, and to the production of a relatively poor tar.

This overcracking is especially disadvantageous where it is desired to use the tar for the manufacture of road compounds. It is present common practice in such manufacture to use water gas tar as a thinning medium for coal gas tar. The water gas tar produced under the above described conditions of overcracking is likely to be heavier than coal gas tar and valueless as a thinner for it. Its value as a fuel is only a fraction of its value as a road compound material.

When the heavy oil is vaporized on the generator fuel bed by spraying it onto the fuel bed top, which has been heated by secondary combustion of the producer gas generated by the primary blast and the ordinary directions of gas and vapor flow recited above are employed, the oil vapors encounter excessive temperatures in the carburetor, especially its top, and in the bottom of the superheater to a lesser degree. If the oil is vaporized in the empty carburetor, the vapors encounter excessive temperatures in the base of the superheater.

The use of the back run and its application of the well known counterflow principle is ordinarily advantageous in water gas manufacture, as it recuperates heat from the heat storage vessels and returns it to the generator. In the use of heavy oil, however, it tends to aggravate the excessive local temperature conditions above described.

It is an object of the present invention to obviate the setting up of such excessive temperature conditions and at the same time to recuperate heat from the heat storage by means of the down run steam, returning the heat to the fuel bed by way of the portion of the set utilized for the heavy oil vaporization. It is the further

object of the invention to control the temperature in at least a portion of the heat storage by selectively controlling the direction of the flow of the down run steam therethrough.

- 5 The invention will be more particularly described in connection with the attached figures which form a part of this specification and in which,

Figure 1 shows a partial elevation and partial 10 vertical cross section of a carbureted water gas set equipped with means for vaporizing heavy oil on the top of the fuel bed.

Figure 2 shows a partial elevation and partial 15 vertical cross section of a carbureted water gas set with heavy oil vaporized in an empty carburetor.

Referring to Figure 1,

1 is the generator, 2 an ignited fuel bed, 3 and 20 4 are air and steam supply means for up air blasting and steam running respectively. The generator is further provided with the secondary air supply means 5, including the bustle pipe 6 and pipes 7 for marginally air blasting adjacent the top of the fuel bed. 8 is an oil supply means 25 arranged to spray heavy oil onto the marginally heated ring at the top of the fuel bed. The top of the generator thus forms a hydrocarbon vaporization apparatus. The generator is further provided with the gas offtake 9 provided with valve 30 10 leading to the carburetor 11.

The carburetor may or may not contain the checkerbrick 12. 13 is a steam supply means at the top of the carburetor and 14 a steam supply means at its base.

35 The carburetor is connected by pipe 15 to the superheater 16, which is provided with checkerbrick 17. The superheater is provided with the stack valve 18. The gas offtake 19 leads through the reversing valve 20 to the washbox 21, connection 22 provided with valve 23 leads to storage or other disposal. The superheater may be further provided with the gas offtake 24 leading to the waste heat boiler 25 and thence to the stack 26. 27 is a stack valve.

45 The superheater is provided with connection 28 provided with valve 29 leading to the top of the generator. 30 is a steam jet. Carburetor 11 and superheater 16 thus form heat exchange apparatus.

50 The generator is provided with the gas offtake 31, leading through the reversing valve 20 to the washbox 21. Superheater 16 is provided with steam inlet 32 near its base and with steam inlet 33 near its top.

55 In operation—the fuel bed is blasted with air supplied through 4 and the resultant producer gas burned with secondary air supplied through 5, 6 and 7, thereby storing heat in the fuel bed and producing a marginal hot zone at the fuel 60 bed top. The blast gases are led through the carburetor and superheater and waste heat boiler and their heat stored. During this operation valves 10 and 23 are open and valve 29 closed. The reversing valve is set to close line 31.

65 After the air blow step, an uprun is made with steam supplied at 4, and the resultant water gas carbureted with oil sprayed through oil supply means 8 onto the marginal hot ring at the fuel bed top. The water gas and resultant oil vapors 70 pass through the offtake 9 and through the carburetor and superheater where the vapors are fixed to oil gas, the resultant carbureted water gas passing by way of offtake 19 to the washbox and thence by connection 22 to storage.

75 During this operation, valves 18, 23 and 29

are closed, valve 10 is open and the reversing valve set to open connection 19 and close connection 31.

After the uprun, valve 10 is closed, valve 29 opened and the reversing valve reversed to close offtake 19 and open offtake 31. A down run is made with steam admitted to the carburetor at 13. The steam passes down through the carburetor and up through the superheater, thence by way of connection 28 to the top of the fuel bed and down through it. The resultant water gas passes by way of connection 31 to the washbox and thence to storage.

After the down run a short uncarbureted uprun is made as a purge and the cycle repeated.

In the down run above described, the down run steam admitted to the top of the carburetor reduces the high temperature there. Steam may also be admitted during the down run at 14 or 32 for ensuring a reduction of the temperature in the base of the superheater.

The desired tendency of this method of operation is the leveling of temperatures throughout the carburetor and superheater. Heat is carried from the hotter portions to the cooler portions instead of the reverse, as in the back run operation, and the maximum temperature in the heat storage vessels is closer to the average temperature.

Although other steps of the cycle, as for instance the blow, may intervene between the down run and the uprun carbureting step the maximum temperature to which the oil vapors are exposed is lower than if ordinary directions of steam flow are followed. According to the present invention although the total heat in the heat storage need not necessarily be less than, when operating according to ordinary methods, the maximum temperature to which the oil vapors are exposed is less and overcracking is avoided.

As an example and purely for illustration, with the introduction of down run steam at 13 and if the temperatures of the carburetor top, carburetor base and superheater base are 1800° F. and 1500° F. and 1500° F., respectively at the start of the down run, they may be reduced by the down run steam to 1500° F., 1500° F. and 1300° F. respectively.

If the continued employment of the above described operation results in too high a temperature at the superheater top, back runs may be made as needed with steam supplied at 333 and passed through the superheater and carburetor and down through the fuel bed, the resultant water gas passing by way of connection 31 to the washbox. In such operation valves 29, 18 and 23 are closed and valves 10 and 22 open. The reversing valve 20 is set to open line 31 and close line 19.

Referring to Fig. 2,

33 is the generator, provided with an ignited fuel bed 34. 35 is an air supply means for up air blasting. 36 is a steam supply means for uprunning. 37 is a secondary air supply means.

The generator is further provided with the gas offtake 38 leading to the carburetor 39. The carburetor is devoid of checkerbrick and is provided with the oil supply means 40 including a nebulizing spray. Carburetor 39 thus forms a hydrocarbon vaporization apparatus. The connection 41 provided with valve 42 leads from the carburetor to the superheater 43. The superheater is provided with the checkerbrick 44 and with the stack valve 45. The superheater thus forms a heat exchange apparatus. Gas offtake

46 leads from the superheater to the waste heat boiler 47 which is provided with the stack 48 and stack valve 49.

The superheater is also provided with the gas offtake 50 leading through the reversing valve 51 to the washbox 52. Offtake 53 provided with valve 54 leads from the washbox to storage or other disposal.

The superheater is further provided with the connection 55 provided with valve 56 and leading to the base of the carburetor and is provided with the steam supply means 57 for introducing steam to the superheater base for down running. Steam supply means 58 for introducing steam to the top of the superheater may also be provided for back running.

The generator is provided with the gas offtake 59, leading from below the fuel bed to the washbox by way of the reversing valve 51.

20 In operation—the generator fuel bed is blasted with air supplied at 35 and the resultant producer gases burned in the carburetor and superheater with secondary air supplied at 37, storing heat in the carburetor and superheater, passing 25 from the superheater through the waste heat boiler and thence to the stack.

In this step valves 42 and 49 are open, valve 56 is closed and the reversing valve set to close offtake 59.

30 After the air blow step, an uprun is made with valves 45, 49 and 56 closed and valves 42 and 54 open and the reversing valve set as before. Steam is supplied to the fuel bed at 36, the resulting water gas passing through the carburetor and 35 superheater in series, where it is carbureted by spraying heavy oil into the carburetor through oil supply means 40. The resultant water gas passes through connection 50 to the washbox and to storage.

40 After the uprun, the reversing valve is reversed, opening line 59 and closing line 50. Valve 42 is closed and valve 56 opened. Steam is admitted to the base of the superheater at 57, passed up through the superheater reducing the high temperature in the superheater base and superheating the steam which passes by way of connection 55 to the carburetor and from the carburetor to the generator top by way of connection 38. The superheated steam passes down through the fuel bed, the resultant water gas passing to the washbox by way of connection 59.

After the down run a short uncarbureted uprun is made as a purge and the cycle repeated.

As described in connection with Figure 1, back 55 runs may be made as desired with steam supplied at 58, superheated in passing down through the superheater and up through the carburetor and thence passing down through the fuel bed, the resulting water gas passing through connection 59 to the washbox. In this step valves 45, 49 and 56 are closed, valves 42 and 54 open and the reversing valve set to open connection 59 and close connection 50.

I do not intend to be limited in the practice of 65 my invention save as the scope of the prior art and of the attached claims may require.

I claim:

1. A process of manufacturing carbureted water gas in a device including a generator containing an ignited fuel bed, a hydrocarbon vaporization apparatus, and heat exchange apparatus, which process includes the following steps: one step being, air blasting the ignited fuel bed to incandescence, burning the blast gases and conducting them in one direction through said va-

porization apparatus and said heat exchange apparatus, and storing heat therein; another step being, introducing steam to said fuel bed, generating blue water gas therein, vaporizing oil in said vaporization apparatus, carbureting the said water gas with said oil vapors, and fixing said carbureted water gas in said heat exchange apparatus; and another step being, passing steam through said heat exchange apparatus in the same direction as the blast gases, and passing 10 said steam and the resulting gases through said vaporization apparatus and said fuel bed in a direction opposite to that of the blast gases, thereby generating gas in said fuel bed.

2. A process of manufacturing carbureted water gas in a device including a generator containing an ignited fuel bed, a hydrocarbon vaporization apparatus, and heat exchange apparatus, which process includes the following steps: one step being, air blasting the ignited fuel bed to 20 incandescence, burning the blast gases, and conducting them in one direction through said vaporization apparatus and said heat exchange apparatus, and storing their heat therein; another step being, making an uprun with steam 25 through said fuel bed, generating blue water gas therein, vaporizing oil in said vaporization apparatus, carbureting the said water gas with said oil vapors, and fixing said carbureted water gas in said heat exchange apparatus; and another 30 step being, passing steam through said heat exchange apparatus in the same direction as the blast gases, and passing said steam and the resulting gases through said vaporization apparatus and said fuel bed in a direction opposite to that of 35 the blast gases, thereby generating gas in said fuel bed.

3. A process of manufacturing carbureted water gas in a device including a generator containing an ignited fuel bed, a hydrocarbon vaporization apparatus, and heat exchange apparatus, which process includes the following steps: one step being, air blasting the ignited fuel bed to incandescence, burning the blast gases and conducting them in one direction through said vaporization apparatus and said heat exchange apparatus, and storing heat therein; another step being, introducing steam to said fuel bed, generating blue water gas therein, vaporizing oil in said vaporizing apparatus, carbureting the said water gas with said oil vapors, and fixing said carbureted water gas in said heat exchange apparatus; another step being, passing steam through said heat exchange apparatus in the same direction as the blast gases, and passing said steam and the resulting gases through said vaporization apparatus and said fuel bed in a direction opposite to that of the blast gases, thereby generating gas in said fuel bed; and another 50 step being, making a back run with steam through said heat exchange apparatus, through said vaporization apparatus, and through said fuel bed, in a direction opposite to that of said blast gases, thereby generating gas in said fuel bed.

4. A process of manufacturing carbureted water gas in a device including a generator containing an ignited fuel bed, a hydrocarbon vaporization apparatus, and heat exchange apparatus, which process includes the following steps: one step being, air blasting the ignited fuel bed to 70 incandescence, burning the blast gases and conducting them in one direction through said vaporization apparatus and said heat exchange apparatus, and storing heat therein; another step being, introducing steam to said fuel bed, gener-

ating blue water gas therein, vaporizing oil in said vaporizing apparatus, carbureting the said water gas with said oil vapors, and fixing said carbureted water gas in said heat exchange apparatus; another step being, equalizing the temperature in said heat exchange apparatus by introducing steam to the heat exchange apparatus adjacent the hottest part of the apparatus, passing said steam through a part of the apparatus 5 in the same direction as the blast gases, and passing said steam and the resulting gases through said vaporization apparatus and said fuel bed in a direction opposite to that of the blast gases, thereby generating gas in said fuel bed; and another step being, making a back run with steam 10 through said heat exchange apparatus, through said vaporization apparatus, and through said fuel bed, in a direction opposite to that of said blast gases, thereby generating gas in said fuel bed.

20 5. A process of manufacturing carbureted water gas in a device including a generator containing an ignited fuel bed, a hydrocarbon vaporization apparatus, and heat exchange ap-

paratus, which process includes the following steps: one step being, air blasting the ignited fuel bed to incandescence, burning the blast gases and conducting them in one direction through said vaporization apparatus and said heat exchange apparatus, and storing heat therein; another step being, introducing steam to said fuel bed, generating blue water gas therein, vaporizing heavy oil in said vaporizing apparatus, carbureting the said water gas with said oil vapors, and fixing said carbureted water gas in said heat exchange apparatus; and another step being, preventing the exposure of the oil vapors and oil gas to too high a degree of heat by equalizing the temperature in said heat exchange apparatus by introducing steam to the heat exchange apparatus adjacent the hottest part of the apparatus, passing said steam through a part of the apparatus in the same direction as the blast gases and passing said steam and the resulting gases through said vaporization apparatus and said fuel bed in a direction opposite to that of the blast gases, thereby generating gas in said fuel bed.

EDWIN L. HALL.
